UNITED STATES PATENT OFFICE.

EDWARD O. HOLMES, OF MALDEN, MASSACHUSETTS.

STEAM-BOILER FURNACE.

SPECIFICATION forming part of Letters Patent No. 428,609, dated May 27, 1890.

Application filed October 28, 1889. Serial No. 328,460. (No model.)

To all whom it may concern:

Be it known that I, EDWARD O. HOLMES, of Malden, in the county of Middlesex and State of Massachusetts, have invented a new 5 and useful Improvement in Steam-Boiler Furnaces, of which the following is a specification.

The object of this invention is to so construct the furnace as to facilitate the cleaning out of the vertical flues, and I accomplish this object by supporting the boiler pivotally, thereby enabling it to be swung down into a horizontal position, thus rendering the flues easily accessible.

15 The nature of the invention in detail is fully described below, and illustrated in the accompanying drawings, in which—

Figure 1 is a vertical section of a steam-boiler furnace embodying my invention, the 20 broken lines showing the position of the boiler when swung down into a horizontal position. Fig. 2 is a vertical section of the same, taken at right angles with the section shown in Fig. 1. Fig. 3 is a horizontal section on line *x*, Fig. 1.

Similar letters of reference indicate like parts.

A represents the rear wall, and A' the side walls, of the furnace.

30 B is the fire-space, C the fire-pot, and D the ash-pit, all constructed as usual.

E is the boiler, provided with the ordinary vertical flues *e*. This boiler is supported by the hollow axes or trunnions F F', having 35 their bearings in the side walls of the furnace. The feed-pipe H, which supplies the boiler, extends into the trunnion F and is suitably packed at *h*. The steam-pipe I, which supplies steam to the building to be 40 heated, is provided with a coupling J, as shown, below the roof A'' of the furnace.

When the flues are to be cleaned out, the coupling J is loosened, a wrench or other suitable instrument applied to one of the 45 trunnions, and the boiler easily swung down into a horizontal position, as shown by the

broken lines in Fig. 1, and the flues thus rendered easily accessible in all their parts.

A horizontal guard or partition K surrounds the boiler and rests on the trunnions, such 50 guard conforming to the shape of the boiler and furnace, thus filling up the space at that point and preventing the flames from passing above it. The rear wall A is provided with a ledge *a*, on which the rear edge of the guard 55 K rests when the boiler is in its usual vertical position, thus holding the boiler steady and preventing undue strain on the coupling J.

Access to the boiler when it has been swung down for cleaning is had by means of doors L. 60

It will readily be seen that the boiler-flues may be cleaned with little difficulty and great thoroughness, thereby enabling them to be kept free and the heat from the fire to be more completely utilized.

65 Having thus fully described my invention, what I claim, and desire to secure by Letters Patent, is—

1. In a steam-boiler furnace, the combination, with the side walls A', rear wall A, and 70 front thereof, of a pivotally-sustained upright boiler provided with upright flues, said boiler being surrounded by the horizontal guard or partition K, resting on the trunnions, conforming to the shape of the boiler and the 75 furnace and filling up the space at that point, whereby the flames are absolutely prevented from passing above it, substantially as set forth.

2. In a steam-boiler furnace, the combination of the side walls A', roof A'', rear wall A, provided with the horizontal ledge *a*, doors L, the pivotally-sustained boiler E, the partition K, the rear edge of which rests on said ledge, trunnions F F', pipe H, and pipe I, provided 85 with the coupling J, substantially as described.

EDWARD O. HOLMES.
